Patented Nov. 2, 1926.

UNITED STATES PATENT OFFICE.

GEORGE SEEDS, OF NEWTON, IOWA, ASSIGNOR TO AUTOMATIC ELECTRIC WASHER COMPANY, A CORPORATION OF IOWA.

ADJUSTABLE POWER-DRIVEN WRINGER FOR WASHING MACHINES.

Application filed August 15, 1919. Serial No. 317,681.

This invention relates to a power driven wringer attachment for a washing machine wherein the wringer is adjustable to swing through a complete revolution of 360 degrees for proper disposition with reference to tubs or other containers used in conjunction with the washing machine, and is also adjustable vertically to various heights, and in all of its adjustments is at all times connected to the power drive of the machine.

It is an object therefore of this invention to construct a wringer attachment for a washing machine (or other device) which is power driven and may be adjusted to any angle of use desired and may also be adjusted vertically without disconnecting the power drive therefrom for any position of adjustment, or during adjustment thereof.

Other and further important objects of this invention will be apparent from the disclosures in the drawings and specifications.

The invention (in a preferred form) is illustrated in the drawings and hereinafter more fully described.

Drawings.

Figure 1 is an elevation view illustrating a frame (of a washing machine) having a wringer embodying the principles of my invention associated therewith.

Figure 2 is a central vertical section taken through the telescopic upright for the wringer showing the interior driving connections.

Figure 3 is an enlarged sectional detail taken on line 3-3 of Figure 2.

Figure 4 is an enlarged sectional detail taken on line 4-4 of Figure 2.

Figure 5 is an enlarged sectional detail on line 5-5 of Figure 1 with parts omitted and parts shown in elevation.

Description.

A frame 1 is provided of conventional design for a wash tub or container for the clothes such as is generally provided in washing machines. Mounted in the lower portion of the frame 1 is an electric driving motor 2, driving a shaft 3 journalled at its far end in a bearing 4 on the frame and having a bevel pinion 5, which meshes with a bevel gear 6. The bevel gear 6 is secured upon the lower end of a short upright or vertical shaft 7, the lower end of which is journalled in a bearing 8. A bracket 9 is secured upon the side of the frame 1, and bolted thereover and secured thereto, is a circular flange 10, of an upright tubular member or standard 11. Slidably mounted in telescopic relation over the upright tubular member 11 is another tubular member or wringer support 12, having a gear or rack 13 formed or secured longitudinally on one side thereof and comprising at its upper end a flanged collar 14 having a plurality of notches 15 in the periphery thereof and a tubular extension 16 upon which is pivoted a bracket 19 upon which a wringer 18 is secured and a latch bolt 20 secured to the bracket is effective through a spring 21 for locking the bracket and wringer in adjusted position with respect to the collar 14. Thus the wringer support comprising the vertical member 12 and bracket 19 allows horizontal and vertical adjustment of the wringer.

The latch bolt 20 is provided with a pivoted actuating handle 22 secured on the lower side of the wringer at one end thereof. Attached to the frame 1 on the upper portion adjacent the telescopic cylinder 12, are brackets 23, and a reel 24 is journalled therebetween and has coiled thereabout a cable 25, one end attached to the reel and the other end attached to the lower end of the cylinder 12. Mounted within a cored portion of the reel 24 is a spiral spring 26, one end attached to the reel and the other upon a shaft 27, on which the reel is journalled. The spring 26 has an initial stress such that it tends to wind the cable 25 thereon to thereby lift the cylinder 12. The spring thus acts as a balancing means tending to support the wringer on the telescopic cylinder 12, in its upper position. Also mounted upon the frame 1, in a suitable position for the purpose, is a pinion 29, meshing with the rack 15, of the cylinder 12, and said pinion is provided with a hand-operating wheel 30. A pawl 31, is pivoted adjacent to the pinion 29, and operates to normally interlock therewith to positively hold said pinion from clockwise rotation (referring to Fig. 1), and support the wringer and its associated elements in adjusted position.

As shown in Fig. 2, the short vertical shaft 7, to which the gear 6, is secured, is secured in an upright tubular shaft 32, hav-

ing a square passage. The tubular shaft 32 is enclosed within the tubular upright 11, and said tubular shaft 32, is telescopically engaged by a squared shaft 33. The upper 5 end of the squared shaft 33, is cylindrical and extends through the tubular member 16, and into the housing 17, containing the driving gears for the rolls of the wringer.

The operation is as follows:—

- 10 The rolls of the wringer may be suitably operated by controlling mechanism mounted within the housing 17, and driven from the motor. The vertical shaft 7, is attached to the tubular shaft 32, within the tubular member 11. The shaft 32, provided with the squared passage has telescoping therewithin the squared shaft 33, which projects upwardly through the tubular member 12, into the housing 17, containing the wringer-roll 15 driving gears. The cylinder 12, is mounted telescopically over the upright tubular member 11, and it is clear, by reference to Figure 2, that as the tubular member 12, is moved upwardly or downwardly over the tubular member 11, to elevate or lower the wringer 18, the driving shafts 32 and 33, slide in telescoping relation without impairing the drive therebetween.

When it is desired to adjust the wringer 20 to any particular height, the pawl 31, is withdrawn from the pinion 29, and the hand wheel 30, is operated in one direction or the other to elevate or lower the wringer by rotation of the pinion 29, which is in engagement with the rack 13. Owing to the fact that substantially all the weight of the wringer and its associated mechanisms are balanced by the cable connection 25, to the spring reel 24—26, very little effort is required to elevate or lower the wringer 25 mechanism.

The wringer is not only adjustable for different elevations but it is also laterally adjustable, i. e., it is capable of swinging 30 through a complete revolution of 360 degrees and being locked in any one of a number of angled positions most convenient for use. This is due to the fact that the bracket 19, supporting the wringer 18, is rotatably 35 mounted upon the upper tubular extension 16, and in order to hold the wringer in any one of its adjusted or rotated positions, the spring-impelled latch bolt 20, is provided,

to engage with one of the notches 15, of the flanged ring 14, on the upper end of the cylinder 12. Said latch bolt 20, is operable into release position by the actuating handle 22.

Details of the gear mechanisms within the housing 17, are not shown as these are a well known type and no illustration thereof is necessary for disclosure of the features of operation of the elevating and adjusting mechanism of the wringer.

I am aware that numerous details of construction may be varied through a wide range without departing from the principles of this invention, and I therefore do not purpose limiting the patent granted otherwise than necessitated by the prior art.

I claim as my invention:

1. In a device of the class described, a standard, a wringer support vertically adjustable on said standard, a wringer on said support, extensible driving mechanism extending through said standard and support for operating said wringer, and means for vertically adjusting said support.

2. The combination with a wringer, of a support therefor capable of both vertical and horizontal adjustments, and extensible driving mechanism for said wringer extending through said support and adjustable simultaneously with the vertical adjustment of the wringer.

3. In a device of the class described, a standard, a wringer support vertically adjustable on said standard, a wringer mounted on said support, means for adjusting said support, and a yielding device connected to said support for balancing said wringer and support during the vertical adjustment thereof.

4. In a device of the class described, a standard, a support having gear teeth vertically adjustable on said standard, a wringer supporting bracket pivoted on said support, a wringer on said bracket, a gear wheel co-acting with said gear teeth for elevating or lowering said wringer, and means for balancing the weight of the wringer during the adjustments thereof.

In testimony whereof I have hereunto subscribed my name.

GEORGE SEEDS.
